ANTIFRICTION MOUNT FOR THE DISTRIBUTOR PLATE OF MOTOR VEHICLE DISTRIBUTORS

Harry Henrichs, Fresno, Calif.

Application January 30, 1953, Serial No. 334,310

6 Claims. (Cl. 200—31)

1

This invention relates generally to an improvement in ignition distributors for motor vehicle engines.

In particular the invention is directed to, and it is a major object to provide, a novel mount for the distributor plate in a distributor of the type wherein said plate is rotatably supported, being part-turned to advance or retract the ignition by means of a vacuum responsive actuator.

In this type of ignition distributor, especially after some wear which occurs in conventional mounts, there is a tendency for the distributor plate to wobble slightly relative to its axis, causing arcing and burning of the breaker points, and resultant imperfect engine operation.

It is therefore another important object of this invention to provide an anti-friction, non-wearing, mount which effectively supports the distributor plate against such undesirable wobble, and yet permits part-turning of the plate by the vacuum responsive actuator.

An additional object of the instant invention is to provide a mount, for the purpose described, which includes a relatively small-diameter, precision ball bearing unit engaged between a hub fixed axially on and depending from the distributor plate, and a sleeve bushing fixed in the distributor case and upstanding about the distributor shaft.

A further object of this invention is to provide an anti-friction mount, for a distributor plate, constructed so that the distributor shaft, though rotating at high speed, cannot adversely affect the mount or cause any wear of the anti-friction parts of such mount.

It is also an object of the invention to provide an anti-friction mount, for a distributor plate, which is designed for ease and economy of manufacture, and long life, without requiring manual attention or service other than normal lubrication.

Still another object of the invention is to provide a practical and reliable anti-friction mount, for a distributor plate, and one which will be exceedingly effective for the purpose for which it is designed.

These objects are accomplished by means of such structure and relative arrangement of parts as will fully appear by a perusal of the following specification and claims.

The figure of the drawing is an enlarged elevation, mainly in section, of an ignition distributor embodying the present invention.

Referring now more particularly to the characters of reference on the drawings, the invention

2

is here illustrated in connection with an ignition distributor of the type which includes a cup-like case 1 supported centrally from below by an integral neck 2; the case 1 being fitted on top thereof with a distributor cap 3.

The distributor plate is indicated at 4, and the latter supports the breaker point assembly 5 worked by the cam 6 on the upper end of the driven distributor shaft 7 which extends upwardly through the supporting neck 2.

The distributor plate 4, when mounted as hereinafter described, is part-turnable about the shaft 7 as an axis by means of a control rod 8 connected at one end to said plate, and thence extending 15 out of the case 1 to connection with a vacuum-responsive actuator 9; said actuator part-turning the plate 4 against the load of a tension spring 10 connected between said plate and an upstanding pin 11.

To this extent the distributor is generally conventional; the improved mount for the distributor plate 4—and which mount embodies the essence of the present invention—being constructed as follows:

A sleeve bushing 12 is fixed in the supporting neck 2 and projects upwardly into the case 1, terminating immediately below the cam 6; the distributor shaft 7 running freely in said sleeve bushing 12.

A relatively small-diameter hub 13 depends from the distributor plate 4 in surrounding relation to the sleeve bushing 12, but clearing the latter, as at 14. The hub 13 is fixedly secured to the distributor plate 4 by annularly grooving 25 said hub at the upper end portion, as at 15; the distributor plate 4 having a central circular opening so that said plate seats closely in the groove 15, with the upper end portion of the hub being peripherally outwardly deformed, as at 16, to lock the plate and hub in fixed engagement.

In the lower half of the depending hub 13, the same is cut with an annular notch 17 which opens inwardly and downwardly, and a precision, annular ball bearing unit, indicated generally at B, of relatively small diameter, is press-fitted into the notched portion 17 of said hub 13. The outer race 18 thus tightly engages in the notched portion of the hub 13, while the inner race 19 is press-fitted onto the sleeve bushing 12 directly 40 above the bottom of the case 1. The lower edge of the inner race 19 seats on a washer 20 in the bottom of the case above the sleeve bushing 12; such washer being of sufficient thickness that it supports the ball bearing unit B with the outer race 18 in clearance relation to said bottom of

the case. The hub 13 has clearance, as at 21, relative to the upper edge of said inner race 19.

With the above described mount, the distributor plate 4 is effectively precision mounted for non-wobbling, anti-friction rotation about the sleeve bushing 12 by means of the vacuum responsive actuator 9.

Because of the fact that the hub 13 has no contact with the sleeve bushing 12, the distributor plate 4 part-turns very easily without friction or binding, and the relatively small diameter of the ball bearing unit B assures that such part turning of the plate can occur without undesirable wobble relative to the axis of the distributor.

Further, as the mount is carried on the fixed bushing sleeve 12, rather than on the rotary distributor shaft 7, as in conventional distributors, there is no wear resulting from rotation of said shaft, and its rotation cannot in any way adversely affect the mounting and operation of the distributor plate.

The result is that with the use of the described anti-friction mount, for a distributor plate, better engine operation is attained than with conventional mounts.

From the foregoing description it will be readily seen that there has been produced such a device as will substantially fulfill the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A distributor plate mount for an ignition distributor which includes a case having a neck depending therefrom, a driven shaft extending upwardly through the neck into the case, and a distributor plate surrounding the shaft in clearance relation above the bottom of the case; said mount comprising a sleeve bushing fixed in the neck and projecting above said bottom of the case, the shaft being rotatable in the sleeve bushing, a hub fixed on and depending from the distributor plate about the sleeve bushing, and an anti-friction bearing engaged between the hub and sleeve bushing.

2. A distributor plate mount for an ignition

distributor which includes a case having a neck depending therefrom, a driven shaft extending upwardly through the neck into the case, and a distributor plate surrounding the shaft in clearance relation above the bottom of the case; said mount comprising a sleeve bushing fixed in the neck and projecting above said bottom of the case, the shaft being rotatable in the sleeve bushing, a hub fixed on and depending from the distributor plate about the sleeve bushing, and a precision ball bearing unit engaged between the sleeve bushing and hub supporting the latter for anti-friction rotation.

3. A distributor plate mount, as in claim 2, in which the precision ball bearing unit is of relatively small diameter whereby to prevent wobble of the distributor plate relative to its axis.

4. A distributor plate mount for an ignition distributor which includes a case having a neck depending therefrom, a driven shaft extending upwardly through the neck into the case, and a distributor plate surrounding the shaft in clearance relation above the bottom of the case; said mount comprising a sleeve bushing fixed in the neck and projecting above said bottom of the case, the shaft being rotatable in the sleeve bushing, a hub fixed on and depending from the distributor plate about the sleeve bushing, the hub having an annular inwardly opening notch therein, and a press-fit precision ball bearing unit in the notch engaging about the sleeve bushing.

5. A distributor plate mount, as in claim 4, in which the ball bearing unit includes an outer race and an inner race; the hub, at the top of the notch, being in clearance relation to the upper edge of said inner race, and above the notch said hub being in clearance relation to said sleeve bushing.

6. A distributor plate mount, as in claim 5, including a washer surrounding the sleeve bushing and seating on the bottom of the case; said washer supporting the inner race from below and in a plane such that the outer race is in clearance relation to said bottom of the case.

HARRY HENRICHES.
